UNITED STATES PATENT OFFICE.

ALBERT C. FISCHER, OF CHICAGO, ILLINOIS.

SHINGLE AND SHINGLE STRIP.

Application filed January 30, 1922. Serial No. 532,720.

Heretofore, in composition strip shingles, either in slabs or continuous strips, it has been customary to cut out a portion of the roofing material between shingle tabs so as to define the outline of the tabs. In this manner, when the roofing is laid up, the part that is exposed to the weather usually is the space the depth of the slot dividing the shingle tabs, so that an underlying section is usually provided to prevent wind or moisture penetrating beyond to the sheathing boards. In this manner the shingle effect and a waterproof understructure are secured.

Other methods consist of defining by printed lines or other convenient methods, spaces simulating shingles, but these methods heretofore have not given the heavy roof effects and have always required an extension as a waterproof foundation.

The herein described invention consists of a roofing strip which in its simplest form, is formed into shingle areas, and along the edges of the areas the material is bent upon itself, creating a lower level than the raised area and by folding the adjacent section, creating a shingle area, and folding the material upon itself the lower level forms a channel and at the same time there is no break in the roofing material. Adjacent areas may thus be made into rectangular or other pattern shingle areas, and by means of folding the material upon itself a series of shingle effects may be secured without cutting or imprinting the roofing, and a heavy appearance is lent to the roofing after it is formed.

The advantage is primarily a heavy roofing effect. Secondly, there is no loss of roofing material or cutting necessary, except along horizontal lines. Thirdly, alternate layers can be placed one above the other, having the channels of successive layers lie midway between two adjacent channels of the preceding layer, thus obtaining a beautiful heavy shingle effect.

The folding of the material upon itself is best effected after having had placed thereon the slate, or other suitable finishing material; but it can readily be understood that this roofing material may be so shaped out of materials which do not require grit or slate surfacing materials. Also grit or slate surfacing material may be placed on the shingle areas after the same are formed, thus leaving the channels without the finish-

ing material, obtaining different roofing effects.

Various methods of folding the shingle area upon itself may be devised, and by laying successive layers a heavy roofing effect is secured with considerable less material than is at present necessary to obtain similar effects.

It is not necessary at all times to fold the material so that a channel is effected in order to secure the desired effect. A number of effects may be secured, especially in the hexagon shape, by folding the shingle area in a hexagon pattern upon a lower stratum of preceding hexagon shaped areas, so that there would be only one fold upon itself on either side of the shingle or upon two of its diagonal edges.

Likewise, effects may be secured in which the shingle area is cut in other forms, such as, a T shape, in which the stem of the T may be permitted to shape itself into the channel by slightly indenting the connecting point with the main shingle area by slots, permitting the depressing of the edges of the T stem into the channels of the preceding layer, thus giving a beautiful bent effect on the T stem and allowing a part of the shingle area to fit down over the preceding channels, thus waterproofing the overlapping edges.

Again the channels formed between the shingle areas may be wide spaced channels, thus simulating the wide spaced effects, or the shingle areas may be diamond shaped and two of the edges of the diamond shape folded upon a preceding connecting series of diamond shaped areas, thus forming the outline of the diamond shape of the preceding area by folding the succeeding series back upon it, the upper and lower edges being cut to pattern.

The invention can best be understood by referring to Figure 1, which represents a perspective of a portion of roofing strip, with depressed channels between the shingle areas, caused by folding two of the edges of the shingle area upon a depressed area, which becomes the channel separating the shingle areas.

This strip may be formed in two or more shingle areas, or in a continuous strip of shingle areas.

In Figure 2, the illustration represents a perspective of a portion of roofing strip, which has been formed into shingle areas,

in which the shingle area is depressed and a ridge is formed between the shingle areas, separating the areas, so that when placed in staggered relation in succeeding layers a shingle effect is secured. The depressed shingle areas are formed by forming a dividing ridge and folding its edges upon the depressed shingle areas.

In Figure 3 is shown a perspective view 10 of a shingle strip in which the shingle areas have been cut to form T's and which shingle areas are separated from each other by depressing an intermediate area by folding two of the edges of the shingle area of the greater bulk upon themselves, thus forming channels between the large areas of the shingles with a depending projection forming the stem of the letter T, which when laid in successive layers the stem is inserted in the 20 channels by depressing its edges along the slots, as shown at the connecting point between the stem and the main shingle area. This permits of sliding the stem into the channels and allowing a portion of the overlapping section of the succeeding area to overlap the preceding strip, thus waterproofing the joint.

In the proper form the stem should be sufficiently long so that when the succeeding 30 strip is pulled down to the proper depth the lower edge of the shingle stem will correspond with the lower edge of the channel.

Referring again to Figure 1, —a— represents the shingle areas produced by bending the edges of the shingle area upon itself and depressing an adjacent narrower area, forming the upper bend —b— and the lower bend —c— so that the base of the channel —i— is formed which lies between two adjacent shingle areas, extending between the horizontal edges of the roofing strip.

In Figure 2 —a— represents the depressed shingle area —j— an elevated narrower area formed by depressing the shingle area and 45 folding the narrower area along its vertical edges upon itself, so that the folds rest upon the depressed area, thus forming a raised dividing area —j— with the raised bend —d— and the lower bend —e—, the raised 50 ridge or dividing area extending between the horizontal edges of the strip.

Figure 3 represents a strip of roofing so severed that the shingle areas —a— have projecting stems —af— which are adapted 55 to fit in the channels —i—, formed by depressing the channel area along the shingle area, thus forming a bend as at —b— and a bend as at —c—. The projections —af— are adapted to fit into the channels —i— by 60 depressing the edges of the stem —af— which can readily be done by reason of the slots —k— extending inward from the connecting neck of the main shingle area and the stem.

65 It may readily be understood that the

channels —i— at the base may be so cut that the stems may be taken from this channel upon severing the roofing sheet in its original cutting, in which case the stem —af— would be comparatively short and fit into 70 the upper half of the channel, which is formed in the same manner as in the present shingle, but it would permit of the formation of depending shingle tabs, as shown in Figure 5.

In this manner the original roofing sheet 75 can be cut without waste, as shown in Figure 6.

Figure 4 illustrates a perspective view of another design of roofing strip which is severed in hexagon formation in such a manner that a sufficient area is permitted for the formation of hexagon shingles in series, the lower or depressed series having folded upon it the succeeding series of hexagon shingle 85 areas.

Referring particularly to Figure 4, —a— represents the upper hexagon shingle series and —h— a depressed hexagon shingle area in the preceding series, which has folded upon itself at —g— the succeeding hexagon shingle areas as shown. The fold is made by effecting a bend as at —b— on two of the edges of the hexagon area, representing the upper area and a bend at —c— connecting the lower area and folding the upper area upon the lower area by creasing the folds as shown. Succeeding layers of shingle slabs or strips are arranged to overlap 90 the edges of the upper series of the preceding strip or slab in this design. While there are the same number of folds the shape of the shingle causes the depressed shingle area to assume the shape of a hexagon shingle 100 instead of a channel, as shown in the previous figures.

Figure 5 illustrates a perspective view of a roofing strip to lay as in Figure 3, in which the strip is cut from a roofing sheet, evenly divided so that there will be no waste 110 of material. The stem of the T area is taken over that part of the shingle area forming the channel —i— when depressed by folding the edges of the shingle at the bend —b— and —c—. In this manner depending tabs are formed as at —l— which are held down by inserting the stem —af— in the remaining part of the channel —i— of the preceding series of shingles.

It will be seen that the forms shown in 120 Figures 3, 4, and 5 correspond in principle, in that in each of them the series of shingle like members in one plane are formed to extend beyond the areas thereof through which they are connected to the members of the strip lying in a different plane, and these extending members are adapted to lap 125 with the members in an adjacent series.

Figure 6 illustrates a plan view of a 130 roofing sheet previous to being severed

along the lines —m— and by forming the shingle areas shaped into the sheet, as shown in Figure 5.

It may readily be understood that various styles of shingle strips or slabs may be formed by forming shingle areas created by folding the edges of the shingle area in such a manner that the fold creates all or part of the outline of the shingle. In combination 10 with the cutting of the strip or the partial cutting of a shingle formation many other forms of shingle areas may be effected.

What I claim is:

1. Roofing strips simulating shingles, comprising a series of shingle-like members alternately in upper and lower planes, and offsetting portions extending between and integrally uniting limited portions of the shingle-like members of one plane with 20 those of the other plane; the shingle-like members of one plane having portions projecting therefrom beyond the portions through which they are thus integrally united with the members of the other plane; 25 said projecting portions being adapted to overlap the shingle-like members of an adjacent series.

2. Roofing strips simulating shingles, comprising a series of shingle-like members alternately in upper and lower planes, and offsetting portions extending between and integrally uniting limited portions of the shingle-like members of one plane with those of the other plane; the shingle-like 35 members of one plane having portions projecting therefrom beyond the portions through which they are thus integrally united with the members of the other plane;

said projecting portions being adapted to overlap the shingle-like members of an adjacent series; and said projecting members being adapted to lap with the portions in a different plane of an adjacent series.

3. Roofing material comprising a series of shingle-like members lying in one plane, 40 with intervening trough-like portions integral therewith but lying in a different plane; said shingle-like members being provided with projections in position to enter the trough-like portions of an adjacent series of 45 similarly constructed roofing.

4. Roofing material comprising a series of shingle-like members lying in one plane, with intervening trough-like portions integral therewith but lying in a different plane; 50 said shingle-like members being provided with projections in position to enter the trough-like portions of an adjacent series of similarly constructed roofing; said projections being connected with the shingle 55 like members over a reduced area which permits the projections to be flexed into a reduced transverse dimension to facilitate entering the trough-like portions.

5. In roofing material, a series of shingle-like members of substantially T-form, integrally connected by a series of intervening trough-like portions lying in a different plane; the portions of the shingle-like members simulating the stems of the T's in one 60 series being adapted to enter the troughs formed in an adjacent series.

Signed at Chicago, Illinois, this twenty-eighth day of January, 1922.

ALBERT C. FISCHER.
